UNITED STATES PATENT OFFICE

2,598,395

AIR PREHEATER FOR FURNACES

Charles A. Larson, Fergus Falls, Minn., assignor
of one-third to Leopold Pistner, St. Paul, and
one-third to Geoffrey W. Welch, Fergus Falls,
Minn.

Application March 20, 1947, Serial No. 736,053

3 Claims. (Cl. 110—56)

1

This invention relates to preheaters for supplying air at unusually high temperatures for combustion in furnaces and/or for reducing the moisture content and facilitating the ignition of solid sub-bituminous or other low grade fuels.

It is an object of my invention to provide a highly efficient heater of this class having air conduits or tubes which are exposed to intense radiant heat within the combustion chamber of a furnace.

A further object is to provide a heater of this class which is adapted to furnish large amounts of air at controlled temperatures ranging above 600 degrees F.

Another object is to provide an air heater with means for feeding air at room temperature and pressure above atmospheric to a multiplicity of metallic heater tubes exposed to direct radiation from burning fuel in the combustion chamber and to protect such tubes from the effect of excessively high or damaging temperature by locating them in close proximity or heat exchange relation to water wall tubes within the combustion chamber.

The invention also includes certain other novel features of construction which facilitate control of the temperature and pressure of the hot air delivered by the apparatus.

Referring to the accompanying drawings which illustrate, by way of example and not for the purpose of limitation, a preferred embodiment of my invention:

Figure 1 is a front elevational view showing my air pre-heater mounted on the front wall of a furnace adapted to burn sub-bituminous fuel;

Fig. 2 is a plan view of the heating apparatus together with a fragmentary portion of the front furnace wall in horizontal section;

Fig. 3 is a fragmentary elevational view showing particularly the arrangement of air tubes and water wall tubes as viewed from the interior of the furnace, a fragmentary portion of the furnace wall being shown;

Fig. 4 is a fragmentary vertical section through the furnace front wall, showing my air heating apparatus partially in side elevation and partially in vertical section, together with a portion of a chain grate stoker for the furnace;

Fig. 5 is a detail plan view showing three of the hot air discharge nozzles and adjacent portion of the header;

Fig. 6 is a detail side view of one of the nozzles and showing the header in section, and

Fig. 7 is an end view of one of the nozzles.

My improved air heater is shown in connection with a steam generating furnace having a front wall 8 and side walls 9 (Fig. 4) of suitable refractory material. The front wall 8 is formed with a combustion arch 10 projecting above a fuel gate 11 into which fuel 12 may be fed by suitable

2

means, e. g., a traveling chain grate stoker indicated diagrammatically at 13 in Figs. 1 and 4. Combustion of the fuel takes place in the chamber indicated generally at 14 (Fig. 4).

The air preheating apparatus comprises a multiplicity of thin walled metallic tubes 15 extending in parallel relation one to another upon the inner surface of the wall 8 and severally connected at their upper and lower ends respectively to headers 16 and 17 mounted exteriorly of the furnace. The tubes 15 may be constructed from high chromium steel or other high temperature resistant alloy. Air at room or atmospheric temperature is supplied to the header 16 by motor driven blowers 18 connected respectively to branches 19 of an air conduit 20 communicating with the central portion of the header 16. Another branch 21 of the conduit 20 extends downward from the branches 19 and is connected to the header 17 at a central point. The conduit 20 and each of the branches 19 and 21 are provided with dampers, indicated at 22, to permit selective restriction of the flow of air through these conduits.

From the ends of the header 17 air conduits 23 extend downward and laterally at an elevation below the grate 13 where these conduits are connected together by a pipe 24 from which the hot air is carried upward through a pipe 25 to an outlet header 26 above the grate 13. From the header 26 a multiplicity of nozzles 27 project horizontally to discharge heated air directly into the body of fuel 12 as it is carried into the combustion chamber. Good distribution of the hot air in the body of fuel is afforded by providing a multiplicity of nozzles 27 which have laterally elongated discharge ends 27a. Heat expansion joints 28 are provided intermediate the ends of the conduits 23 and 21 and these and the other conduits and piping carrying the high temperature air may be encased in suitable heat insulating material.

The portions of the air tubes 15 which are exposed to direct radiation within the combustion chamber 14 extend in parallel relation and closely adjacent to water wall tubes 29 which also extend upon the inner surface of the wall 8. Water is supplied to the lower ends of the tubes 29 from a header 30 and the water, as it is heated in the tubes 29, rises and is collected in a header at their upper ends, not shown. Each of the tubes 15 extends between and closely adjacent to a pair of tubes 29 and both sets of tubes are mounted flush with the wall 8. This arrangement of the air and water tubes is advantageous but other arrangements may be employed. For example, one set of tubes may extend across the other set in heat exchange relation thereto and thereby maintain within safe limits the maximum temperatures attained by the air tubes during the operation of the furnace.

Operation

In operation, as fuel is consumed in the combustion chamber 14, temperatures ranging from 1700 to 2000 degrees F. may be reached at the inner surface of the wall 8 upon which the tubes 15 and 29 extend. The tubes 29 are maintained at a much lower temperature by the water flowing therein. The blowers 18 are preferably of the constant pressure type. Air at room temperature is drawn into the blowers 18 and is forced at high velocity through the branches 19, conduit 20 and header 16 and thence through the several tubes 15. In passing through these tubes the air is heated to the desired high temperature and then flows from the header 17 through the conduits 23, pipes 24 and 25 to the header 26 from which it is discharged at high velocity and temperature into the combustion chamber. As indicated in Fig. 4, the hot air is preferably injected and distributed uniformly through the body 12 of fuel where it enters the combustion chamber through the gate. This is particularly advantageous where the fuel has a high moisture content and is difficult to ignite, as in the case of sub-bituminous fuels, including lignite. My apparatus affords means for injecting air at temperatures of from 600 to 800 degrees F. into a body of such fuel so that the moisture content is rapidly reduced and the fuel is caused to ignite readily and to be consumed efficiently in the furnace.

The temperatures attained by the portions of the tubes 15 exposed to direct radiation within the combustion chamber are limited not only by the air passing at high velocity through these tubes but also by the cooling effect of the adjacent water wall tubes 29. This has been found to be advantageous as a safeguard against rapid deterioration of the air tubes where they are exposed to the intense heat of direct furnace radiation.

Control of the temperature and pressure of the air delivered through the conduits 23 is afforded by my arrangement of the by-pass conduit 21 and dampers in this and the conduit 20 and branches 19. By suitable manipulation of the damper 22 in the conduit 21, a controlled amount of the air at substantially room temperature may be bypassed into the header 17 when it is desirable to deliver air at a temperature below the maximum. The cool, by-passed air merely mixes with the high temperature air in the header 17. The velocity of flow through the heating tubes 15 may also be regulated by manipulation of the dampers in the conduit 20 and branches 19 extending to the blowers. By adding high temperature pre-heated air to that required for combustion, increased efficiency results even where preheating and drying of the fuel is not required. In either case, improved combustion results from supplying air at temperatures ranging from 600 to 1000 degrees F. or at somewhat lower temperatures where this is desirable.

It will be evident that high temperature air supplied by my apparatus may be utilized for various purposes other than those specifically described herein, without departing from the spirit of my invention as defined in the appended claims.

Having described my invention, what I claim as new and desire to protect by Letters Patent is:

1. In a furnace adapted to burn sub-bituminous fuel and having a traveling grate for feeding such fuel into the combustion chamber and spaced parallel water wall tubes exposed to direct

radiation from the source of heat in said chamber, an air preheater comprising, a plurality of metal tubes each extending along, in the space between and in heat exchange relation to adjacent water wall tubes and exposed to direct radiation from the flame within the furnace combustion chamber and at an elevation above said grate, means for supplying air at room temperature and at pressure above atmospheric to said tubes, said tubes being formed and arranged to heat the air discharged therefrom to temperatures above 600 degrees F., a conduit communicating with said tubes to receive the air heated therein and hot air discharge nozzles arranged to receive air from said conduit and to discharge the air directly into and below the upper surface of the body of fuel entering the combustion chamber on said grate.

2. In a steam generating furnace having a combustion chamber and spaced parallel water wall tubes exposed to direct radiation from the source of heat within said chamber, a multiplicity of metallic air tubes each extending along, in the space between and in heat exchange relation to adjacent water wall tubes within the combustion chamber and exposed to direct radiation from the source of heat therein, a header communicating with the several air tubes at one end thereof, a blower for supplying relatively cool air to said header and a conduit arranged to receive heated air from said tubes, said water wall tubes limiting by heat exchange the temperature of the air tubes within the combustion chamber.

3. In a steam generating furnace having a combustion chamber and water wall tubes exposed to direct radiation from the source of heat within said chamber, a multiplicity of metallic air tubes disposed in heat exchange relation to said water wall tubes within the combustion chamber and exposed to direct radiation from the source of heat therein, a header communicating with the several air tubes at one end thereof, a blower for supplying relatively cool air to said header, a conduit arranged to receive heated air from said tubes, said water wall tubes limiting by heat exchange the temperature of the air tubes within the combustion chamber, a by-pass for cool air extending from said blower to said conduit and dampers adapted to selectively restrict the flow of air through said by-pass and to said air tubes whereby the temperature of the air delivered from said conduit may be controlled and limited by additions of controlled quantities of cool air from said by-pass.

CHARLES A. LARSON.
